UNITED STATES PATENT OFFICE.

ROBERT FRED. TOCHTERMANN, OF MUNICH, GERMANY.

DESIGN FOR A MEMBER OF COMBS.

SPECIFICATION forming part of Design No. 29,404, dated September 27, 1898.

Application filed July 16, 1898. Serial No. 686,153. Term of patent 14 years.

To all whom it may concern:

Be it known that I, ROBERT FRED. TOCHTERMANN, a subject of the King of Bavaria, residing at Munich, Bavaria, Germany, have 5 invented a certain new and useful Design for a Member of a Comb or Hair-Retainer, of which the following is a specification.

In the drawings, Figure 1 is a face view of the member. Fig. 2 is an edge view of the same.

The design consists in a curved side *a*, having an eye at one end, with teeth projecting laterally from the curved side, said teeth being of different length, so that their ends will

be in line, the said side ending in an extension *b*, having a curved end.

As shown in Fig. 2, the member is curved from front to rear, forming a concave rear face.

I claim—

The design for a member of a comb herein shown and described.

In witness whereof I have hereunto set my hand in presence of two witnesses.

ROBERT FRED. TOCHTERMANN.

Witnesses:

OTTO MUNRO,
H. L. BEIL.
